CONTAINER WITH FOLDABLE SIFTER SPOUT

Sam Kamin, Houston, Tex.

Application November 10, 1953, Serial No. 391,280

3 Claims. (Cl. 222—189)

This invention relates to improvements in containers for granulated or pulverized materials, such as salt, flour, spices and medicinal and toilet powders, having foldable spouts provided with sifting means for the contents of the containers.

It is among the objects of the invention to provide in containers for such materials as salt, flour, spices and powders, an opening for the discharge of the contents therefrom, a spout structure movably mounted on the container for movement into and out of closing relationship to the container opening and effective when in its open position to direct the container contents discharged through the opening in a predetermined direction relative to the container, and which includes sifting means mounted in the spout and effective when the spout is in open position, to sift the contents discharged from the container and regulate the rate of such discharge; in which the spout and sifter means may constitute permanent components of the container assembly or may be provided as a separate attachment for containers not originally provided with such components; and in which the spout and sifter attachment is economical to manufacture, easy to apply to a container of known construction, and greatly increases the convenience of the container.

Other objects and advantages will become apparent from a consideration of the following description and the appended claims in conjunction with the accompanying drawing, wherein:

Figure 1 is a fragmentary perspective view of a container and spout assembly illustrative of the invention;

Figure 2 is a fragmentary cross sectional view on the line 2—2 of Figure 1 showing the spout in closed position;

Figure 3 is a view similar to Figure 2, but showing the container tilted and the spout in open position;

Figure 4 is a fragmentary cross sectional view on the line 4—4 of Figure 3;

Figure 5 is a fragmentary cross sectional view on the line 5—5 of Figure 3; and

Figure 6 is a plan view of a blank from which the spout assembly is formed.

With continued reference to the drawing, the illustrated container assembly comprises a box at 10, of rectangular shape and formed of suitable sheet material, which may include materials, such as cardboard, heavy paper, sheet metal, or a combination of sheet metal and cardboard or paper, and includes a flat top wall 11 having therein an opening 12 extending from a location intermediate the length of the top wall to a front wall 13 disposed perpendicular to the top wall with its top edge extending along the edge of the top wall to which the opening 12 extends, and side walls 14 and 15. The assembly also includes a spout assembly, generally indicated at 16, of right angular cross sectional shape including a flat, imperforate wall 17 of rectangular shape and formed of a suitable material, such as light weight sheet metal, and a flat perforate wall 18 of rectangular shape joined along one edge and to the related end of the

2

wall 17. The perforate or sifter wall 18 includes a panel 20 which may be a piece of light weight sheet metal or paper suitably perforated, a piece of perforated sheet plastic, a piece of wire or plastic mesh screen or other suitable material, as may be desired.

5 Sector shaped wings 23 and 24 have their straight side edges to the side edges of the walls 17 and 18 substantially perpendicular thereto. The panel 20 is marginally secured, as at 21, by soldering or brazing along the straight side edges of the wings 23 and 24 remote from the imperforate wall 17 and along the free edge of the perforate wall 18.

10 The juncture 19 of the walls 17 and 18 of the spout 16 is provided with a sleeve 26 and a hinge pin 27 extends through the sleeve 26 along the inner side of the juncture 19 and has lateral arms 28 and 29 on its opposite ends and substantially perpendicular thereto, and disposed substantially in the same plane. The arms 28 and 29 are laterally inwardly offset at their outer ends to provide fingers 30 and 31 respectively. The fingers are inserted through holes provided in the box side walls 14 and 15 below and near the top edges of the side walls and spaced from the front wall 13 with the fingers bearing against the inner sides of the box side walls.

15 The spout 16 is pivotally mounted on the box with the perforate wall 18 within the box and its imperforate wall 17 outside of the box, so that the spout is movable between open and closed positions. In the closed position of the spout 16, as illustrated in Figures 1 and 2, the imperforate wall 17 of the spout engages the upper side of the top wall 11 of the box in covering relationship to the opening 12 with the wings 23 and 24 extending through this opening, and with the perforate or sifter wall 18 substantially against the inner surface of the front box wall 13.

20 In the fully open position of the spout 16 the sifter wall 18 is disposed against the lower side of the box top wall 11 in covering relationship to the opening 12 and the imperforate wall 17 and wings 23 extend upwardly from the top wall 11 with the imperforate wall extending substantially in vertical alignment with the front wall 13. In this open position of the spout 16, as illustrated in Figure 3, the wings 23 and 25

24 and the wall 17 provide a spout for pouring the contents of the box from the opening 12 in a predetermined direction, and the perforate wall 18 provides a sifter disposed in covering relationship to the opening 12 in the top wall 11 of the box to sift the contents as it leaves the box through the opening 12 and controls the rate and direction of distribution of the contents. The movement 30 of the spout 16 from the closed position shown in Figures 1 and 2 to the open position shown in Figure 3, is limited by stop lugs 34 and 35 projecting laterally outwardly beyond the sides of the perforate wall 18 and engageable with the under side of the box top wall 11. The lugs 35

35 are lateral extensions on the wings 23 and 24 respectively, see Figure 6, and are bent 90° from the plane of the respective wings so as to extend laterally outwardly therefrom toward the respective side walls 14 and 15 of the box 10. As the spout 16 is moved into the open position shown in Figure 3, the stop lugs 34 and 35 abut against the underside of the top wall 11 so as to limit further opening movement of the spout 16.

40 The imperforate front wall 17 has medially of its length and at its free edge a raised portion 32 which serves as a finger lip for moving the spout from its closed position.

45 The spout and sifter attachment can be provided as a permanent component of a container during the manufacture of the container, if desired, or may be provided as a separate attachment which can be applied to an existing container by cutting a proper opening in the top wall of the container, puncturing the side walls of the con-

tainer near the opening and inserting the arms of the hinge pin 27.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. The combination with a box having spaced side walls having side edges, a top wall having a front end, a front wall having an upper end and a pouring opening in said top wall spaced from said side walls, said opening reaching from a point intermediate the ends of said top wall to a point near said front end of the top wall, a spout comprising an imperforate wall having a free end and another end, a perforate sifter wall having a free end and another end, said imperforate and perforate walls being disposed at right angles to each other and being fixed together at their other ends so as to define a juncture, sector wings extending between said imperforate and perforate walls and secured thereto along their side edges, said imperforate wall being wider than said pouring opening and being located above said top wall and said perforate wall being disposed within the box below said top wall, hinge means hinging said sector wings to the box side walls.

4
on an axis adjacent to said juncture and located near to the front end of the top wall and the upper edge of the front wall.

2. The combination of claim 1, wherein said sector wings have laterally outwardly projecting stop lugs on said sector walls extending beyond opposite sides of the perforate wall and arranged to bear against the under side of the box top wall in an open position of the spout.

3. The combination of claim 1, wherein said hinge means comprises a sleeve secured to and extending along the juncture of the spout, a hinge pin extending through said sleeve, said hinge pin having lateral arms on its opposite ends bearing against the outer sides of the box side walls, said lateral arms having portions traversing and journaled in openings provided in the box side walls, said portions terminating in laterally inwardly offset fingers bearing against the inner sides of the box side walls.
